UNITED STATES PATENT OFFICE.

EPHRAIM PUTNAM, OF SCHUYLER FALLS, NEW YORK.

BARREL.

SPECIFICATION forming part of Letters Patent No. 371,703, dated October 18, 1887.

Application filed December 15, 1886. Renewed September 13, 1887. Serial No. 249,590. (No model.)

To all whom it may concern:

Be it known that I, EPHRAIM PUTNAM, a citizen of the United States, residing at Schuyler Falls, in the county of Clinton and State 5 of New York, have invented certain new and useful Improvements in Barrels; and I do declare the following to be a full, clear, and exact description of the invention, such as will enable others skilled in the art to which it applies to make and use the same, reference being had to the accompanying drawings, and to the letters and figures of reference marked thereon, which form a part of this specification.

My invention relates to an improvement in barrels in which the head can be readily and securely adjusted and be easily detached. I attain these results by the mechanism illustrated in the accompanying drawings, in which—

20 Figure 1 represents a vertical section of the barrel with the head removed and the barrel open. Fig. 2 represents a vertical section of the barrel with the head in position and the barrel closed. Fig. 3 is a detailed view of the head of the barrel. Fig. 4 is a detailed view of the bar detached from the barrel. Fig. 5 is a detailed view of the fastening.

Similar letters refer to similar parts throughout the several views.

30 The chines *a a* of the barrel *A A* are cut down so as to leave a shoulder, *b b*, on the inside of the barrel, upon which the head *B B* of the barrel rests when closed. A fastener, *D D*, is constructed of metal, having a shoulder, *g g*, the projection of which will be equal to the thickness of the barrel-stave. The shoulder *g g* of the fastener *D D* is provided with a slot, *h h*, in which a pin, *f f*, is attached, so as to allow it to turn in the slot. The pin *f f* is provided with a screw-thread extending from the point where it is fitted into the slot up to within a short distance of the top of the pin, which is made square, so as to allow the pin to be turned by a key fitted over it.

45 The fastener *D D* is riveted upon one side of the barrel, the chine of the barrel being cut away sufficiently to allow the shoulder *g g* of the fastener to project over the stave, and so the top of the pin *f f* will be on a level with the 50 top of barrel-chines. On the opposite side of the barrel, in juxtaposition to the fastener *f f*,

a hinge, *d d*, is riveted, to which is connected a bar, *C C*, having in the opposite end a female thread, *e e*, constructed to fit and engage with the thread upon the pin *f f*.

55

The head of the barrel *B* is constructed so as to closely fit within the chines *a a* of the barrel, resting upon the shoulders *b b*, and is provided with two cross-pieces, *c c*, placed parallel to and at such distance from each other 60 as to allow the bar *C* to slip between them when the barrel is closed, these cross-pieces serving as handles to strengthen and keep in position the head *B*.

The operation of closing and opening the 65 barrel is as follows: The head *B* is placed in position, fitting within the chines *a a* of the barrel, and rests upon the shoulder *b b*, having the cross-pieces *c c* on a line with the fastener *D*, so that when the bar *C*, working upon the 70 hinge *d d*, is brought over the head *B* it will fit in between the cross-pieces *c c*. The bar *C* is brought over the head *B*, the female thread *e e* passing over the top of the pin *f f* until it reaches the screw-threads on the pin *f f*. A 75 key fitting the top of pin *f f* is then inserted, by which the pin *f f* is turned, causing the threads of the female thread *e e* to engage the threads upon the pin *f f* sufficiently to hold the bar *C* firmly in place, the bar *C* being on a level with 80 top of the barrel-chines. The barrel is opened by inserting the key upon the pin *f f* and turning the pin *f f*, causing the threads of the slot *e e* and pin *f f* to disengage, and the bar *C* being lifted up, the head *B* is readily removed. 85

What I claim as my invention, and for which I desire Letters Patent, is—

1. The combination of a barrel having the chine cut down so as to form a shoulder for the head to rest upon and closely fit therein, 90 with a hinged bar provided in one end thereof with a metal female screw-thread fitting and engaging with a screw-pin rotating in the shoulder of a metal plate fastened upon the side and top of the barrel, substantially as 95 herein described, and for the purposes set forth.

2. The combination of the barrel having the chine cut down so as to form a shoulder for the head to rest upon and fit closely therein, with a hinged bar provided with a female 100 screw-thread on one end thereof passing over a threaded pin turning in the body of the bar-

rel and securing the head in position, substantially as described, and for the purposes herein set forth.

3. The combination of a metal fastener provided with a screw-threaded pin rotating in a slot in the shoulder thereof, with a hinged bar having in one end thereof a metal screw-threaded slot constructed to engage with the

screw-threaded pin by means of a key, substantially as herein described and set forth. 10

In testimony whereof I affix my signature in presence of two witnesses.

EPHRAIM PUTNAM.
